(57) CLAIM

The ornamental design for a bed headboard and footboard, as shown and described.

DESCRIPTION

FIG. 1 is a left front perspective view of a bed headboard and footboard showing my new design;

FIG. 2 is a front elevational view thereof; and,

FIG. 3 is a side elevational view, the opposite side being a mirror image thereof.

The views of the bed headboard and footboard not shown form no part of the claimed design. The broken lines depicting bed rails, optional ornamentation on headboard and feet represent environmental elements only and form no part of the claimed design.
